UNITED STATES PATENT OFFICE.

CHESTER B. SHEPARD, OF MELROSE, MASSACHUSETTS.

DESIGN FOR A SPOON OR SIMILAR ARTICLE.

SPECIFICATION forming part of Design No. 36,567, dated September 22, 1903.

Application filed July 27, 1903. Serial No. 167,250. Term of patent 3½ years.

To all whom it may concern:

Be it known that I, CHESTER B. SHEPARD, a citizen of the United States, residing at Melrose, in the county of Middlesex and State of Massachusetts, have invented a new and original ornamental Design for Spoons or Similar Articles, of which the following is a specification, reference being had to the accompanying drawings, forming part thereof.

Figure 1 of the drawings is a front view, and Fig. 2 is a back view, of my design.

What I claim as new, and desire to secure by Letters Patent, is—

The ornamental design for a spoon or similar article, as shown.

In testimony whereof I have signed my name to this specification in the presence of two subscribing witnesses.

CHESTER B. SHEPARD.
